UNITED STATES PATENT OFFICE.

ADOLPHUS E. THOMPSON, OF BRANTLEY, ALABAMA.

DESIGN FOR A CULTIVATING-SCRAPER.

SPECIFICATION forming part of Design No. 30,422, dated March 28, 1899.

Application filed March 1, 1899. Serial No. 707,403. Term of patent 14 years.

To all whom it may concern:

Be it known that I, ADOLPHUS E. THOMPSON, a citizen of the United States, residing at Brantley, in the county of Crenshaw and State 5 of Alabama, have invented and produced a new and original Design for a Cultivating-Scraper, of which the following is a specification.

This invention relates to a new and original 10 design for a cultivating-scraper; and it has for its object to provide a design of this character that shall be both useful and ornamental.

The leading feature of the design resides in 15 a central approximately rectangular flat plate provided with a pair of oppositely-extending oblong rectangular wings tapering in cross-section and disposed at an obtuse angle to the central plate, said central plate being further provided with curved lateral offsets or shoulders 20 merging into the wings at and contiguous to the top edges of the latter.

In the drawings, Figure 1 is a perspective 25 view of a cultivating-scraper embodying the design contemplated by the present invention. Fig. 2 is a central transverse sectional view thereof. Fig. 3 is a cross-section on the line 3 3 of Fig. 1.

Referring to the accompanying drawings, the numeral 1 designates a central approximately rectangular flat body-plate provided 30 with a centrally-located circular opening 2 therein and at its opposite side edges with the oppositely-extending oblong rectangular wings 3. The rectangular wings 3 taper in cross-section toward their lower edges and are 35 disposed at an obtuse angle to the central body-plate 1, said central body-plate being further provided at its side edges with the curved lateral offsets or shoulders 4, merging into the wings at and contiguous to the top 40 edges of the latter.

What is claimed is—

The design for a cultivating-scraper, herein shown and described.

In testimony that I claim the foregoing as 45 my own I have hereto affixed my signature in the presence of two witnesses.

ADOLPHUS E. THOMPSON.

Witnesses:

DORIC E. BURKS,
JOHN LEWIS SEGREST.
